INVENTOR.

Arthur Atwater Kent
BY Cornelius L. Chet
Lie ATTORNEY.

UNITED STATES PATENT OFFICE.

ARTHUR ATWATER KENT, OF ARDMORE, PENNSYLVANIA.

DISTRIBUTER STRUCTURE.

1,385,625.

Specification of Letters Patent. Patented July 26, 1921.

Application filed March 30, 1920. Serial No. 370,003.

To all whom it may concern:

Be it known that I, ARTHUR ATWATER KENT, a citizen of the United States, residing in Ardmore, county of Montgomery, and State of Pennsylvania, have invented certain new and useful Improvements in Distributer Structures, of which the following is a specification.

My invention relates to distributer structure such as employed in the high tension circuit of ignition apparatus for internal combustion engines.

It is common in connection with multi-cylinder internal combustion engines to employ in association with a distributer element, rotated in definite relation with the engine, stationary contacts or terminal connected, respectively, to the spark plugs of the different engine cylinders and supported on or carried by a detachable member, generally a cap adapted to house and inclose both the distributer and the timer or interrupter structure, the support or cap carrying also a centrally disposed contact connected with the source of spark producing energy and engaged by a contact on the rotary distributer.

It has been found, particularly when the contact on the rotary distributer is a resilient or yielding one spaced from the distributer, that in replacing the support or cap for bringing it into operative position, the support or cap may be moved laterally while approaching its final or operative position, and in so doing the central contact on the cap or other part and the yielding or resilient distributer contact may engage, causing displacement or injury to either or both.

In accordance with my invention, this difficulty is overcome by limiting the extent to which the yielding or resilient distributer contact may be separated or spaced from the distributer, and so preventing its conflict or engagement with the cap terminal or other part in bringing the cap to its operative position.

My invention accordingly resides in distributer apparatus or structure comprising a distributer having a resilient or yielding contact, co-acting with suitable stationary terminal or contact, with means preventing more than predetermined separation or spacing of the distributer contact from the distributer, though leaving the distributer con-

tact free to yield by movement toward the distributer.

My invention resides in features of structure and combination hereinafter described and claimed.

For an illustration of some of the various forms my invention may take, reference is to be had to the accompanying drawing, in which:

Figure 1 is a sectional view, partly in elevation, of apparatus embodying my invention.

Fig. 2 is a perspective view of the distributer shown in Fig. 1.

Fig. 3 is a longitudinal sectional view of a distributer embodying a modification of my invention.

Fig. 4 is a perspective view, on enlarged scale, of the insert of Fig. 3.

Referring to Figs. 1 and 2, 1 is a base or support to which is attached, as by hook springs 2, the cap 3, preferably of molded insulating material. Upon the base 1 within the cap are mounted timer or interrupter contacts, such, for example, as are employed to control the primary circuit of an induction coil. The movable contact is indicated at 4 and is carried upon an arm 5 actuated by cam 6 to control the co-action of the movable contact 4 with the stationary contact. The cam 6 is formed upon or secured to the cam shaft 7 driven, as well understood in the art, in definite relation with the main shaft of the internal combustion engine whose ignition is controlled by the cam 6. The upper end 8 of the cam shaft extends into a recess 9 in the detachable or removable distributer member or block 10, the latter having at the bottom of the recess 9 the transversely extending rib 11, integral with member 10, engaging in an offset slot in end 8 of the cam shaft, whereby the shaft 8 in rotating rotates the member 10 with it.

Carried by the member 10 is the yielding or resilient contact 12, as of spring steel or the like, secured at its one end adjacent the outer end of the member 10 and extending substantially radially toward its center and upwardly away therefrom, whereby its free end is spaced from member 10 and resists movement toward that member.

The contact 12 may be secured to the distributer member 10 in any suitable way. In the example illustrated it is held by screw 13 threaded into the metallic bushing or in-

sert 14 molded in the distributor block 10. The same screw may secure to the member 10 the metallic brush or terminal 15, whereby the contact 12 and member 15 are in electrical connection with each other.

In the center of the cap 3, that is, substantially co-axial with the shaft 7, is a metallic bushing or insert 16, with which is adapted to be connected one terminal of the source of spark producing energy, for example, one terminal of the high tension secondary winding of an induction coil. On the lower end of said bushing 16 is the projecting terminal or contact 17 adapted to make contact with the distributor contact 12, the contact 12 rotating with the shaft 7 while maintaining contact with terminal 17.

At equal distances from the center of the shaft 7 and suitably angularly or circumferentially spaced are the metallic bushings or inserts 18 molded in or carried by the cap 3 and terminating within the same in the distributor terminals 19, past which the aforesaid brush or terminal 15 rotates, allowing to pass to each in succession spark producing energy delivered to the spark plugs of the engine cylinders by conductors communicating with the bushings or inserts 18.

Molded integral with the member 10, or otherwise suitably provided as hereinafter described, is an upstanding boss or lug 20 having the under cut or recess 21. The boss 35 or lug 20 may originally have no recess 21, or such recess may be formed in the molding operation. To mold the recess 21, however, is more or less difficult, and it is preferred, therefore, that the boss 20 be originally 40 formed complete, and the recess 21 thereafter cut or formed by any suitable means.

The boss 20 and its recess 21 are so positioned that the free end of the spring contact 12 extends into the recess, as indicated in Figs. 1 and 2, the lip 22 limiting the distance away from the member 10 to which the contact 12 may spring. When the distributor is isolated, as in Fig. 2, that is, when not in co-operative position with the cap 3 and its terminals, the spring 12 normally 50 engages the under side of the lip 22.

By this construction, or its equivalent, the distance to which the free end of the contact 12 may spring away from the member 55 10 is limited, yet that contact may yield toward the distributor member 10, as indicated in Fig. 1, while co-acting with the terminal 17 carried by the cap 3. The contact 12 cannot spring away from the distributor block 10 to such distance as might or would interfere with attachment of the cap 3 to the base 1 in the operative position illustrated. With the contact spring 12 extending to too great a distance from 60 the member 10, the cap or some part carried

thereby in being brought to operative position would engage the spring 12, and forcing the cap to position would cause harm either to the part of the cap engaging the contact 12, or the contact 12 itself would be 70 distorted, bent or otherwise undesirably affected.

In lieu of molding the limiting structure integral with the member 10 as above described, it may take the form of a separate 75 piece or insert of metal or insulating material molded in the member 10 in suitable position.

This modification of my invention is illustrated in Figs. 3 and 4, where the member 80 20^a is an insert of metal or insulating material molded in the member 10 and having or forming a recess 21^a below the lip 22^a.

Or the distributor 21 may have molded therein a hole or recess into which there is 85 later inserted or secured a plug of metal or insulating material suitably formed, for example, having a recess and lip as above described.

What I claim is:

1. The combination with relatively rotating distributor member and distributor terminals, one of which is disposed substantially in the axis of rotation, of a contact secured to said member and adapted to 95 spring away from said member toward said one of said terminals, and means on said member for limiting the separation of said contact from said member.

2. The combination with relatively rotating distributor member and cap, of distributor terminals on said cap and one of which is disposed substantially in the axis of rotation, a contact spring secured at its one end to said member and adapted to engage adjacent its free end with said one of said terminals, said spring having a bias to separate its free end from said member, and means on said member limiting the separation of the free end of said contact therefrom.

3. Distributer structure comprising a distributor member, a spring contact thereon secured thereto at its one end and having a free end biased away from said member, and means on said member projecting from a face thereof and limiting the separation of said free end from said face of said member.

4. Distributer structure comprising a distributor member, a spring contact secured thereto at its one end and having a bias tending to separate its free end from said member, and a member on said distributor member having a recess into which the free 125 end of said contact projects.

5. Distributer structure comprising a distributor member, a spring contact secured thereto at its one end and having a bias tending to separate its free end from said 130

distributer member, and a member on said distributer member having a lip spaced from said distributer member, the free end of said contact extending under said lip.

- 5 6. Distributer structure comprising a distributer member of insulating material, a spring contact secured at its one end to said distributer member and having a bias tending to separate its free end from said
- 10 10 distributer member, and a member integral with said distributer member having a projection beneath which the free end of said contact extends.

7. Distributer structure comprising a dis-

tributer member, a spring contact secured at 15 its one end to said distributer member and having its free end at the center of said distributer member, said contact having a bias tending to separate its free end from said distributer member, and a stop on said 20 distributer member extending above the face thereof and limiting the outward movement of said free end of said contact from said face.

In testimony whereof I have hereunto af- 25 fixed my signature this 26th day of March, 1920.

ARTHUR ATWATER KENT.
